UNITED STATES PATENT OFFICE.

ALEXANDER GLINCHIKOFF, OF STOCKTON, CALIFORNIA.

BALL CATCHING AND THROWING RACKET.

Application filed July 20, 1921. Serial No. 486,030.

To all whom it may concern:

Be it known that I, ALEXANDER GLINCHIKOFF, a citizen of Russia, residing at Stockton, county of San Joaquin, State of California, have invented certain new and useful Improvements in Ball Catching and Throwing Rackets; and I do declare the following to be a full, clear, and exact description of the same, reference being had to the accompanying drawings, and to the characters of reference marked thereon, which form a part of this application.

This invention relates to improvements in devices for catching, holding and throwing balls, such as are used in athletic games of various kinds.

The principal object of my invention is to provide a device for the purpose indicated, which is adapted to be held in either hand, and which will positively trap and hold a ball thrown at the device without the use of the other hand, and may also be used to instantly expel and throw the ball, with what ever velocity the operator may desire, without first removing the ball from the device or manually handling it in any way.

Once caught, the ball is automatically trapped, and can only be forcibly expelled by a sweeping stroke imparted to the device by the arm of the user, which imparts centrifugal force to the ball.

At the same time, the ball may be readily extracted by the fingers of the other hand in the event that it is not desired to throw the same.

The device is therefore adaptable for use in any games in which the catching and throwing of balls forms a major part of the game, and in which it is essential that the ball, once caught, shall not be accidentally dropped.

A further object of the invention is to produce a simple and inexpensive device and yet one which will be exceedingly effective for the purposes which it designed.

These objects I accomplish by means of such structure and relative arrangement of parts as will fully appear by a perusal of the following specification and claims.

In the drawings similar characters of reference indicate corresponding parts in the several views.

Fig. 1 is a vertical section of the racket.
Fig. 2 is a front view thereof.

Fig. 3 is an outline diagram showing the 55 catching of a ball.

Fig. 4 is a similar view showing the expelling of a ball.

Fig. 5 is an enlarged fragmentary section taken on a line 5—5 of Fig. 1, showing one 60 of the spring controlled catching fingers.

Referring now more particularly to the characters of reference on the drawings, the numeral 1 denotes a handle of suitable form, fixed onto which and projecting upwardly 65 therefrom is a rigid band 2, preferably circular in form, the handle extending radially thereto.

Mounted radially onto blocks 3 fixed on the inside of the band 2 adjacent the outer edge thereof and projecting toward the center thereof is a plurality of rigid fingers 4 which are hinged to the blocks in such a manner that they can only move away from the outer edge or face of the band, as shown 75 in Fig. 5, these fingers being normally held in a common plane by means of springs 5. The inner ends of these fingers terminate short of each other as shown in Fig. 2 to 80 outline an opening smaller in diameter than the ball 6 which the device is intended to catch.

Fixed onto the handle 1 behind the band and projecting upwardly therefrom at spaced intervals are flexible pins 7 of any 85 desired material and cross-sectional shape, these pins being so formed and placed relative to the band 2 as to outline and enclose a substantially semi-spherical area, considering the plane of the band as the vertical 90 diametrical plane of the sphere. Directly behind the band and fixed to the back of the handle are guide forks 8, positioned intermediate the pins 7, which for their lower portions are curved to follow the semi-spherical contour previously described in common with the pins 7, but which above the plane of the axis of the band project upwardly thereabove.

The pins and forks are all so spaced relative to each other that the ball cannot pass therebetween. The pins 7 at their upper ends terminate short of each other and have upwardly projecting flat springs 9 secured thereto, these springs, together with the 100 band and forks, outlining an opening somewhat smaller than the ball and give to the latter a determined direction of flight.

The pins 7 may if desired be replaced or supplemented by a wire mesh member or some similar structure enclosing an area similar in shape to that outlined by said 5 pins.

In order to reduce the size of the opening left between the band, pins and forks, a wire 10 may be placed about the same, preferably at a point adjacent the major axis of the 10 area enclosed, the length of this wire being capable of being varied by means of adjustment nuts 11 or other means mounted on the band, the wire itself being preferably held in proper alinement by grooved guides 15 12 on the pins and forks. In this manner the outlet may be made to accommodate balls of various sizes.

In operation, the handle is held in the hand with the band facing in the direction 20 from which a ball is being thrown. The ball will then strike the fingers 4, moving them inwardly sufficiently to allow the ball to enter the enclosure formed by the pins and forks, the fingers, as soon as the ball 25 clears the same, at once resuming their normal position and preventing the escape of the ball through this opening.

The ball is then firmly held in the enclosure, and may be instantly thrown by a 30 swinging stroke of the arm of the operator, which causes the ball to move against the guide forks toward the outlet, the force imparted thereto causing the pins and springs therearound to spread sufficiently to allow 35 the escape of the ball. If it is not desired to so expel the ball, it may be removed by merely withdrawing the same through the outlet with the fingers of the other hand.

In ordinary use however, the catching and 40 throwing of the ball may follow each other in rapid sequence, without the necessity of manually handling the ball and having very often to stop and take a new grip on the same after it has been caught.

With my device, no special preparation 45 is necessary for throwing the ball.

From the foregoing description it will be

readily seen that I have produced such a device as substantially fulfills the objects of the invention as set forth herein. 50

While this specification sets forth in detail the present and preferred construction of the device, still in practice such deviations from such detail may be resorted to as do not form a departure from the spirit of the invention, as defined by the appended claims. 55

Having thus described my invention, what I claim as new and useful and desire to secure by Letters Patent, is:—

1. A ball catching and throwing racket 60 comprising a handle, a ball enclosing structure fixed thereon, an intake opening for the enclosure whereby to permit a ball to enter the same, an outlet from said enclosure positioned in a plane at right angles to the 65 plane of the intake, fingers projecting into the intake opening and adapted to yield only in the direction of the enclosure, and springs spaced about the outlet and projecting upwardly therefrom, these springs outlining 70 an opening normally smaller than a ball being used.

2. A ball catching and throwing racket 75 comprising a handle, a rigid continuous band projecting from the upper end of the handle in the plane thereof, guide forks fixed to the handle and projecting upwardly a certain distance from and behind the band, pins between the forks and the edges of the 80 band, said pins forks and band defining a substantially semispherical area, the forks and pins terminating short of each other and of the band adjacent the upper end of the latter whereby to form an outlet for a ball, springs fixed to the pins and projecting 85 upwardly therefrom and arranged to normally outline a smaller area than that at the diameter of a ball, and fingers projecting into the area outlined by the band and arranged to yield inwardly only, to allow a 90 ball to press against and pass into the enclosure.

In testimony whereof I affix my signature.
ALEXANDER GLINCHIKOFF.
